UNITED STATES PATENT OFFICE.

FRED HENRY ROBERTS, OF SOMERVILLE, MASSACHUSETTS.

DESIGN FOR A DISPLAY-BOX.

SPECIFICATION forming part of Design No. 30,010, dated January 17, 1899.

Application filed December 15, 1898. Serial No. 699,387. Term of patent 14 years.

To all whom it may concern:

Be it known that I, FRED HENRY ROBERTS, a citizen of the United States, residing at Somerville, in the county of Middlesex and State 5 of Massachusetts, have invented and produced a new and original Design for a Display-Box, of which the following is a specification, reference being had to the accompanying drawings, forming a part thereof.

10 In the drawings, Figure 1 is a perspective of the holder, representing one side and the front thereof. Fig. 2 is a view in perspective of the holder to represent the other side and the back thereof.

15 As shown in the drawings, the leading or material feature of my design consists of a flat or level rest or support A, rectangular in

shape, and at the rear and highest end of the holder, and an inclined rest or support B, extending from the front edge of said flat rest 20 or support downward to the bead or shoulder a at its lower edge, and which second rest or support is rectangular in shape, and the face C, which is also rectangular in shape and which is sharply inclined from the bead or 25 shoulder a to a base or rest c.

Having described my invention, what I claim as new, and desire to secure, is—

The design for a display-box as herein shown and described.

FRED HENRY ROBERTS.
